By his Attorney

J. B. L. Orme

UNITED STATES PATENT OFFICE.

MAURICE C. WALTER, OF NEW YORK, N. Y., ASSIGNOR TO ASSOCIATED FARMS CO., INC.,
A CORPORATION OF NEW YORK.

SHIPPING-ENVELOP.

1,228,725.

Specification of Letters Patent. Patented June 5, 1917.

Application filed October 6, 1915. Serial No. 54,338.

To all whom it may concern:

Be it known that I, MAURICE C. WALTER, a citizen of the United States, residing in the borough of Manhattan, city, county, 5 and State of New York, have invented certain new and useful Improvements in Shipping-Envelops, of which the following is a specification.

This invention relates to protective covers 10 for use in packaging light cartons, etc., containing various articles of merchandise, and more particularly is directed to an outer envelop for cartons of eggs serving as a convenient substitute for the ordinary 15 type of crate and adapted for shipment by parcel post, etc.

It is to be noted in connection with devices of this type that in practice damage most frequently results from injuries to the 20 edges of the envelop. Most of the strain of handling appears to come upon the edges, and unless they are properly reinforced, causing additional weight and added expense to the structure, they are very apt 25 to break along these lines and permit damage to the goods inclosed.

One of the objects of the present invention accordingly is to provide a light, comparatively inexpensive device of the kind 30 mentioned in which damage to the edges thereof will not occasion damage to the boxes or other receptacles inclosed. Another object of the invention is to provide a device of this type which may be easily 35 erected, and, when positioned about a number of containers, will hold them in compact and readily handleable form. Another object of the invention is to provide a simple and efficient device for holding the walls 40 of the envelop in assembled position about a number of boxes or receptacles. Other objects will be in part obvious and in part pointed out hereinafter.

Referring to the drawings, wherein similar 45 reference numerals designate similar parts throughout, Figure 1 is a perspective view of the envelop ready for shipment; Fig. 2 is a longitudinal sectional elevation taken substantially through the center 50 of the envelop; Fig. 3 is a cross-sectional elevation taken also substantially through the center of the envelop; and Fig. 4 is the blank from which the envelop is formed.

Referring now more particularly to the 55 drawings, and especially to Fig. 4, the en-

velop is shown as comprising a substantially square base portion 1 including edges 2 and 3 formed by scoring the blank and edges 4 and 5 formed by the edges of the blank. Adjoining the edges 2 and 3, respectively, of the base are laterally projecting portions constituting the sides and top of the envelop. Each of these portions are substantially the same and a description of one will suffice for both. Each laterally projecting member 60 includes an oblong 6, one of the longer edges 65 of which is formed by the edge 2, the opposite edge being formed by scoring the blank. The shorter edges 8 and 9 are, respectively, continuations of the edges 4 and 5. Adjoining the oblong 6 and located at the extremity of the blank is an oblong 10, 70 one of the longer edges being formed by the edge 7, the opposite edge being formed by the edge 11 of the blank. The shorter edges 12 and 13 of the oblong 10 are, respectively, 75 continuations of the edges 8 and 9 of the oblong 6. According to the construction outlined, the blank itself is an oblong, with the base portion 1 forming the central portion thereof and the oblongs 6 and 10 constituting the remainder.

A series of notches 14, 15, 16, 17, 18 are disposed at substantially equidistant intervals along the longer edge of the oblong blank. The notches 15, 16 and 17 are substantially centrally placed with respect to the edges 8, 4, 8, while the notches 14 and 18 are respectively adjacent the opposite shorter edges of the oblong. A similarly spaced series of notches 19, 20, 21, 22 and 23 is provided in the opposite longer edge of the blank oblong, the notches 20, 21 and 22 bisecting the edges 9, 5, 9, as heretofore, and the notches 19 and 23 being positioned respectively adjacent the opposite edges 11. The vertices of the two series of notches are arranged in juxtaposition to one another.

Proceeding inwardly from the edge 11 of the laterally projecting member adjoining the edge 2 of the base 1 are the cut-out portions forming part of a locking means spaced from one another and equidistantly disposed respectively from the edges 12 and 13. These locking members each include a channel 24 terminating in a diamond-shaped aperture 25. Projecting inwardly from the opposite edge 11 of the member laterally projecting from the edge 3 of the base 1 are substantially identically disposed locking 100 105 110

members comprising channels 26 and diamond-shaped apertures 27, which, when the blank is erected into shape, conform generally in outline to the locking members 24 and 25. The series of notches and locking members serve to hold a cord in position when the envelop is erected in the manner hereinafter described.

A number of cartons 28 having been mounted one above the other, and an envelop of suitable size having been selected to encompass them, the cartons are placed so that their bottoms lie on the base 1, as shown in Figs. 2 and 3. The oblongs 6 are then folded into a position substantially perpendicular to the base forming thereby the side members. The oblongs 10 are then folded into a position parallel with the base, with that one projecting from the edge 3 of the base 20 overlying its corresponding oblong. When this has been accomplished a slip noose 29 is made in the end of a piece of cord 30, and the noose is passed through the channels 24 until it lies within the diamond-shaped 25 apertures 25.

Holding the noose in this position, the overlying oblong is moved so that the channels 26 permit the noose to pass therethrough to the diamond-shaped apertures 27, and to 30 rest in the latter, when they are positioned in alinement with the apertures 25. Then upon tightening the noose, it will lie in a closed curve, with a portion against the upper surface of the oblong 10 between the adjacent 35 vertices of the diamond-shaped apertures 27, 27 and the intermediate portions resting in the alined vertices 27, 27, 25, 25, and a portion lying against the under-surface of the opposite oblong 10 between the adjacent 40 vertices of the diamond-shaped apertures 25. When the noose has been pulled tight, making a secure fastening of the box, the substantially square end pieces 31, 31 are placed in the open ends inclosed by the edges of the 45 envelop, these end pieces 31, 31 resting against the containers. As so positioned ends 31 lie wholly within the envelop.

The remainder of the band 30 for holding the carton in position inside the envelop is 50 now passed about the outside of the envelop in the manner indicated in Figs. 1, 2 and 3, passing across the upper surface of the envelop, through the notches 14 and 18, which substantially coincide when the box is 55 erected, down to a position substantially intermediate the end member 31, where it is looped, and thence passes at substantially right angles through notch 15, through notch 17, through notch 22, through notch 60 20, thence through the loop and turning at right angles through notch 16, notch 21, and notches 19 and 23, back to the starting point at the loop 29, where it may be conveniently tied.

65 According to the construction described, it

will be noted that the notches 14 to 23 provide seats for the band 30, these seats being remote from the end edges of the envelop. The cord itself is not only thus seated in these notches but by virtue of its position remote from the edges is permitted to retain the cartons 28, 28 or other articles in position remote from the ends of the envelop.

70 As has been pointed out, this is a very important provision in view of the fact that 75 breakage is most apt to occur at the edges of the envelop. By arranging the parts so that the article is held remote from the edges there is little chance for damage to it, even if these outer edges are broken, for 80 when in a broken condition they will still serve as a buffer and ample protection to the edges of the cartons themselves. It will furthermore be observed that by seating the cord in an inwardly offset position from the 85 ends the liability of its breakage by rubbing is materially lessened.

The locking means including the apertures 25 and 27 connected to the edges 11, 11 by the channels 24 and 26 forms in connection with the loop 29 of the cord 30 a highly efficient means for binding together the sides of the envelop and one which requires little time to operate. Of course it will be understood in connection with this locking 95 device that the loop may be separate from the cord member, but it is preferable to provide it as an integral part of the cord, so that the latter may employ it as a starting point in traversing the surfaces of the envelop.

100 It will thus be seen, according to this embodiment, that, among others, the objects heretofore mentioned are achieved.

As many apparently widely different modifications of this invention may be made 105 without departing from the scope thereof, I do not wish to be limited to the description given except as indicated in the appended claims.

Having thus described my invention, I 110 claim:

1. A collapsible envelop, having open ends, a tie-member to tie an article inside said envelop remote from the edges thereof, said tie-member passing across said ends and 115 remote from the edges of the envelop, and retaining walls lying between said tie-member and the ends of the inclosed article.

2. A collapsible envelop having open ends and provided with seats remote from the 120 edges thereof for a cord member, a cord member adapted to tie an article within said envelop remote from the edges thereof, said cord member passing across said ends and seating in the edges thereof, and retaining 125 walls lying between said cord member and the ends of the inclosed article.

3. A collapsible envelop having open ends and provided with notches extending inwardly from and terminating remotely from 130

- the edges of the ends, said notches serving as seats for a cord member, a cord member adapted to tie an article within said envelop remote from the edges thereof, said cord member passing across said ends and seating in the notches therein, and retaining walls lying between said cord member and the ends of the inclosed article.
4. A collapsible envelop of substantially 10 cubical form when erected, having open ends, each of the end edges of whose sides is provided with a seat for a tie-member, a tie-member to tie an article within said envelop remote from the edges thereof, said 15 tie-member passing across said ends and remote from the edges of the envelop, and re-
- taining walls lying between said tie-member and the ends of the inclosed article.
5. A collapsible envelop of substantially 20 cubical form when erected, having open ends, each of the end edges of whose sides is provided with a substantially centrally disposed notch serving as a seat for a cord, a cord adapted to tie an article within said envelop remote from the edges thereof, said 25 cord passing across said ends and seating in said notches remote from the edges of the envelop, and upright retaining walls lying between said cord and the ends of the inclosed article.

MAURICE C. WALTER.
